UNITED STATES PATENT OFFICE.

FREDERICK W. LINAKER AND THEODORE M. BRUBACK, OF DU BOIS, PENNSYLVANIA.

BOILER-SOOT CLEANER.

Application filed April 12, 1921. Serial No. 460,661.

This invention relates to means for cleaning soot from water tubes or flues of boilers by directing against the surfaces to be cleaned a jet or jets of steam or other suitable fluid. In such apparatus it is common to provide a tube entering through the boiler setting into the boiler furnace, and having perforations or jet nozzles for directing jets of steam laterally of such tube, such jets entering either within the boiler flues, or more commonly against the exterior of boiler tubes. Such steam jets tubes or pipes are commonly called soot cleaner elements or soot blowers. Such cleaner elements are sometimes fixed in position within the boiler furnace, and in other cases are removable; in some cases the jets occupy an invariable direction, and in others the cleaner element is rotatable to cause the jets to sweep through a suitable angle and thereby clean a considerable angular range of surface among the boiler tubes.

The present invention relates to soot cleaners which are rotatable or oscillatable, so as to vary the angular direction of the cleaning jets. Such elements, when located down within reach, have a hand wheel or other handle on the outer portion, which may be grasped by an attendant for turning the cleaner element; or when located so high as to be out of reach, they usually carry a sheave wheel over which passes a chain extending down to where it may be reached by the attendant for turning the element. In either case the efficiency of the cleaning of the soot from the tubes depends upon the skill or judgment of the operator. If he turns the element too rapidly, the jets sweep across or past the tubes so fast that they have not time to effectively dislodge the soot; to secure the best results the element should be turned very slowly, or else be given an intermittent movement permitting it to rest in a given angular position long enough for the jets to do their work, and then turned through a small angle to another position and there rest, and so on, until the jets have swung through the prescribed arc, whereupon the same movements should be performed in the contrary direction.

The present invention provides a mechanism whereby such intermittent operation of the cleaner element is assured under such conditions as to afford, under normal operation, a rest or dwell of the element in each

position to which it is advanced, for a sufficient time to afford the jets an opportunity for effectively cleaning the boiler tubes.

To this end the invention provides an operating mechanism in the nature of a reversible ratchet and pawl device, the operating member or element of which requires to be reciprocated by the attendant, and during the movements in one direction the cleaner element is rotated step by step, while during the idle or return movements in the opposite direction the element remains stationary, giving normally the required time for the jets to accomplish the cleaning.

The construction and operation will be apparent from the following description, with reference to the accompanying drawing, wherein—

Figure 1 is a front view, partly in vertical section, on the line 1—1 in Fig. 2;

Fig. 2 is a side elevation partly in vertical mid section;

Fig. 3 is a fragmentary plan showing a stop lug;

Fig. 4 is a fragmentary vertical section on the line 4—4 in Fig. 2;

Fig. 5 is a fragment of Fig. 1 showing the parts in another position;

Fig. 6 is a section of the ratchet wheel showing a removable stop tooth or plug;

Figs. 7 and 8 are a side view and front view of such stop tooth or plug, detached.

Referring first to Fig. 2, A shows a fragment of the boiler wall or setting, usually of masonry, in which is set a sleeve or bushing B, and within this are a stop pipe or spacer sleeve C and a pipe D which for the purposes of the present description, may be treated as the cleaner element (although in practice the outer pipe D is a nipple coupled within the wall A to the cleaner element proper). The cleaner element is essentially a steam pipe extending a suitable distance into the boiler furnace and commonly projecting among the boiler tubes and having a row or rows of perforations or jet nozzles for directing a series of jets of steam (or other fluid) against the soot-covered surfaces of the boiler tubes. The cleaner element is mounted to turn or rotate, usually within angular limits. The details of its construction, being well understood, are not shown. Where the bushing B emerges on the outer side of the wall A, a cap E is commonly applied to hold the pipes C D in place and in central rotative position. The pipe D pro-

jects outside the wall and communicates with a nipple D' which enters through a stuffing box or other means into the connection head F, which receives steam through an inlet pipe G and directs it into the nipple D', the latter being rotated in a stuffing box for making a steam-tight joint with the head F. These parts, so far as described, are common with rotatable cleaner elements.

10 Fixed in connection with the element D is a wheel H by which to turn it. This wheel H takes the place of the sheave wheel ordinarily heretofore applied, and in the construction shown has hubs a a', fastened 70 by set screws b to members D, D', respectively, so that when nipple D' is turned by the wheel H, the element D is also turned.

15 The wheel H, instead of being a sheave wheel, is a ratchet wheel having teeth c c adapted to be engaged by pawls or pawl arms d d', which as shown, are formed integrally as arms upon a double action pawl I. This pawl is pivoted on a pin e to a yoke or rock lever J which is pivoted conveniently upon the hubs a a'. The rock lever J is best constructed of two yoke plates j and j' connected at their ends by pins or bolts f f, which afford a convenient medium for connecting chains g g which 80 hang down suitably far to be conveniently reached by the operator. The plates j j' turn respectively on the hubs a a', being located on opposite sides of the wheel H, and the pawl pin e is connected between them, the pawl I being thus confined between the plates with its arms d d' in position to engage the teeth on the wheel H. On the rear of the pawl projects an arm h to which is connected a contractile spring i the opposite end of which is connected to a lug k on the back of the rear plate j'. The arrangement is such that whichever pawl arm d d' is in engagement with the teeth c, the spring holds the pawl in that position, while yielding to its operating movements; but upon throwing over the pawl to bring the opposite tooth into engagement, the lug h, in passing through a line x or x' connecting k and e, carries the spring to the opposite side 90 of that line, so that its action upon the pawl is reversed. These opposite positions of the pawl are shown respectively in Figs. 1 and 5. The pull of the spring is on line y, Fig. 1, or y', Fig. 5.

18 20 25 30 35 40 45 50 55 60 65 The pawl-carrying lever J is permitted a limited movement just sufficient to enable the pawl in either operative position to push the wheel H the distance from one tooth c to the next. This limitation is accomplished by forming the front plate j with stop projections l l, shown in Fig. 4, and by providing the bottom portion of the head F with a projection m contracted at n (Fig. 3) to form a stop, which is shown in section in Fig. 4. Thus the lever J is limited to a

70 75 80 85 90 95 100 105 110 115 120 125 130 movement equal to the clearance between the free tooth l and the stop n (see Fig. 4), which in the construction shown corresponds to an angular movement theoretically of 15 degrees, the wheel H in this example being shown as provided with 24 teeth (in practice, however, the movement is 20 degrees, including 5 degrees clearance).

The operation as thus far described is that of a ratchet, the operator pulling alternately on the chains g g and thereby rocking the lever J back and forth; on one movement the pawl pushes the wheel H forward the distance of one tooth, and on the return movement the pawl clicks idly over the next tooth, and during this time the element remains stationary, so that its jets are given a period of rest at the inclination determined by the last feeding movement imparted to the element. The operator is thus constrained to permit the element to remain thus stationary for an appreciable time after each forward movement; and in the natural and normal operation this period of rest is sufficient to insure (under otherwise proper conditions, as with a normal steam pressure) an efficient cleaning of the soot from the tubes of the boiler.

18 20 25 30 35 40 45 50 55 60 65 70 75 80 85 90 95 100 105 110 115 120 125 130 It is desirable, and in some locations of cleaner elements it is necessary, to provide a limit to the angular sweep of the jets, and for such purpose it is desirable to automatically reverse the direction of intermittent feed by the pawl and ratchet device. The means for accomplishing this reversal will now be described.

The pawl I is formed with a fragmentary or mutilated pinion I', shown in the drawing as having three pinion teeth, these being formed integrally with the pawl arms d d' and the remainder of the pawl structure. These teeth mesh with similar teeth on a fragmentary gear or pinion K, which constitutes a reversing dog, being pivoted on a pin p fastened to the plate j. The wheel H carries one or more stops L suitably located, so that at the end of the desired rotation of the element in one direction, the last movement of the wheel relative to the lever brings the stop adjacent the reversing dog K to the position shown in Fig. 1; whereupon, on the next or return movement of the lever J, the pivotal pin p of this dog being carried by plate j, is swung in the contrary direction, so that a lug q projecting rearwardly from the dog K strikes the stop L (which is now stationary) and thereby rocks the dog K, and through its geared engagement with the pinion teeth I' throws over the pawl I to its contrary position, as shown in Fig. 5. This movement, as already stated, carries the line of pull of the spring i to the opposite side of the pivot e of the pawl and thereby gives the pawl an operative spring movement in

the contrary direction. The next angular movement of the lever J causes the pawl arm d' to click idly over the next tooth c and engage it, so that upon the contrary movement of the lever J the wheel H is propelled in the opposite direction.

The reversing movements thus occasioned are dependent upon the location of the stop L with reference to the wheel H and element D. For every differently located element it is desirable to be able to limit its movement so as to cause its jets to sweep through a given angle with respect to the boiler tubes; and to render this sweep adjustable, according to the individual requirements of the respective cleaner elements, it is important to make the reversing stops L adjustable relatively to the ratchet wheel H. To accomplish this the stops L are constructed as pins or plugs which may be set in various angular positions with respect to the wheel H. If it is desired that the cleaner elements shall sweep through nearly an entire revolution, only one stop L may be used; otherwise two such stops should be provided, which are set at the required angular distance apart on the wheel H. Various arrangements providing for such angular adjustment of the stop projections or plugs L may be provided.

The arrangement shown affords as many positions for either stop as half the number of teeth on the wheel; that is to say, the wheel is provided, opposite each successive pair of teeth c, with holes r through any one of which the reversing stop or plug L may be inserted. To provide a secure connection, the holes or sockets r are tapered, as shown in cross-section in Fig. 6, and the base of each stop plug L is equally tapered, so that the stop plug may be inserted from the back through any hole r, and forced firmly into place. To provide against the turning of the plug, each socket r and the tapered base s of the plug, are flattened on one side, as shown at s' in Figs. 7 and 8. When the plug has been thus inserted, it requires to be fastened or keyed in place, so that it may not work loose. To accomplish this, provision is made for inserting a pin or cotter t (Fig. 6). To provide suitable seats for this pin in relation to the several holes or sockets r, the wheel H is provided with radial grooves u on its front face, of a depth similar to the diameter of the pin; and while it would be sufficient to form through each plug L a diametrical bore through which the pin t could be driven, it is preferable to form the wedge-shaped base s of the plug with a flaring notch v on its back, as shown in Fig. 7, the depth of this notch being just sufficient to receive the pin t in the position shown in dotted lines in Fig. 7; so that when the pin t is driven into place, it spans coinciding

grooves alternately in the wheel and plug. It must be driven so far in that its end will not project into the space between teeth; and to lock the pin in place the inner end of the radial groove u is rounded, so as to bend the end of the pin forward as it is driven (see Fig. 6).

It will be understood that by this means one or two stop plugs L may be applied in any one of a variety of positions with respect to the wheel H, which, in the precise example shown, are 30 degrees apart. Other spacing and other specific means for locating and attaching the stop pins or plugs may readily be substituted if for any given installation a different arrangement or construction is found preferable.

It will be understood that the invention here described may be variously modified, the precise example shown being only one of many involving the essential features of the invention. It is to be understood, therefore, that the invention is not limited to the precise construction shown, but may be varied or modified to any extent within the scope of the appended claims.

What we claim is:

1. In a soot cleaner, a cleaning element adapted to deliver jets of a cleaning fluid such as steam to certain portions of the tubular surfaces of a boiler, and mechanism for turning such element to swing its jets through an arc only sufficient to deliver jets of cleaning fluid to all the tubular surfaces reached by such cleaner, first in one direction and then in the reverse direction, the movement in each direction being composed of intermittent or step by step movements, whereby the cleaner is brought to rest at a series of stopping points during each swinging movement to deliver jets of cleaning fluid from a temporarily fixed position to parts of the boiler to be cleaned, said mechanism including an actuating device, separate sets of controlling means for said actuating device each requiring an independent movement by the operator to produce each step, said device operating in a continuous cycle of movements, irrespective of the direction of the turning movement of said cleaner element, with means to automatically reverse said turning movements at their limits during such continuous operation.

2. In a soot cleaner, a cleaning element adapted to deliver jets of a cleaning fluid such as steam to certain portions of the tubular surfaces of a boiler, and mechanism for turning such element to swing its jets through an arc only sufficient to deliver jets of cleaning fluid to all the tubular surfaces reached by such cleaner, first in one direction and then in the reverse direction, the movement in each direction being composed of intermittent or step by step movements,

whereby the cleaner is brought to rest at a series of stopping points during each swinging movement to deliver jets of cleaning fluid from a temporarily fixed position to parts of the boiler to be cleaned, said mechanism including an actuating device, separate sets of controlling means for said actuating device each requiring an independent movement by the operator to produce each step, said device operating in a continuous cycle of movements, irrespective of the direction of the turning movement of said cleaner element, with means to automatically reverse said turning movements at their limits during such continuous operation, and such actuating device being adapted to produce a dwell of the cleaning element at each of the positions of rest of the latter during its step by step movement.

3. In a soot cleaner, a cleaning element adapted to deliver jets of a cleaning fluid such as steam to certain portions of the tubular surfaces of a boiler, and mechanism for turning such element to swing its jets through a required arc, first in one direction and then in the reverse direction, the movement in each direction being composed of intermittent or step by step movements, whereby the cleaner is brought to rest at a series of stopping points during each swinging movement to deliver jets of cleaning fluid from a temporarily fixed position to parts of the boiler to be cleaned, said mechanism including an actuating device operating in a continuous cycle of movements, irrespective of the direction of the turning movement of said cleaner element, with means to automatically reverse said turning movements at their limits during such continuous operation, said actuating device comprising a two-armed lever with a flexible operative connection for each arm.

4. In a soot cleaner, a cleaning element adapted to deliver jets of a cleaning fluid such as steam to certain portions of the tubular surfaces of a boiler, and mechanism for turning such element to swing its jets through a required arc, first in one direction and then in the reverse direction, the movement in each direction being composed of intermittent or step by step movements, whereby the cleaner is brought to rest at a series of stopping points during each swinging movement to deliver jets of cleaning fluid from a temporarily fixed position to parts of the boiler to be cleaned, such mechanism including a ratchet wheel and reversible pawls with stops for throwing one pawl into and the other out of operation, and a lever having a continuous cycle of movements and connected with said pawls to move the ratchet wheel in either direction during such continuous operation, said lever having two arms with an operating mechanism at the end of each arm, the move-

ments of both operating mechanisms being necessary to advance the cleaner each step.

5. In a soot cleaner, an intermittent turning means for a cleaner element comprising a ratchet wheel connected thereto, a two-armed lever hung coaxially therewith, a pawl carried by said lever, stops to limit the movements of the lever, and pull connections hung from the opposite arms of the lever, whereby the lever is rocked by pulling down its opposite arms alternately.

6. The combination of claim 5, the lever formed of two plates located on opposite sides of the ratchet wheel and fixed together.

7. The combination of claim 5, the stops comprising stop projections on the rocking lever and a stationary part having a stop projection co-operating therewith to limit the movement of the rocking lever.

8. An intermittent turning means for a rotatable soot cleaner element comprising a ratchet wheel fixed to the element, a rocking lever having a limited angular movement, a reversible pawl carried by said lever, a reversing dog engaging said pawl, and a reversing stop on said wheel adapted to engage said dog to reverse the pawl.

9. The combination of claim 8, the pawl and dog geared together.

10. The combination of claim 8, the dog pivoted to the lever.

11. The combination of claim 8, the ratchet wheel carrying two stops for reversing the pawl in different directions.

12. The combination of claim 8, the ratchet wheel carrying two stops for reversing the pawl in different directions, said stops being relatively adjustable to different angular positions.

13. The combination of claim 8, in which the ratchet wheel has a plurality of sockets and a stop, and in which the stop engages in any of the sockets, the two having reciprocally-engaging non-circular portions for preventing turning of the stop.

14. The combination of claim 8, in which the ratchet wheel has a plurality of sockets and a stop, and in which the stop engages the sockets and the two having reciprocally-engaging non-circular portions for preventing turning of the stop, and in which there are means for fastening the stop in any socket.

15. The combination of claim 8, in which the ratchet wheel has a plurality of sockets and a stop, and in which the stop engages in any of the sockets, the wheel having adjacent to each socket a groove, and a pin adapted to enter the respective groove to engage the stop to hold the latter in place.

In witness whereof, we have hereunto signed our names.

FREDERICK W. LINAKER.
THEODORE M. BRUBACK.
